PAGE 2

I claim:

The ornamental design for a commercial building for a shopping center or the like, as shown.
